RING BINDER

Charles C. Cruzan, Poughkeepsie, N. Y., assignor
to Trussell Manufacturing Company, Pough-
keepsie, N. Y., a corporation of New York

Application July 18, 1936, Serial No. 91,289

11 Claims. (Cl. 129—24)

This invention relates to loose-leaf binders of the split-ring type.

Special objects of the invention are to provide a safe, strong ring binder, which can be easily opened and closed and securely held in both the open and the closed positions, which will not accidentally snap closed, to the injury of fingers or papers and which on the other hand, will not open and release the pages if accidentally dropped or 10 the like, and which furthermore, with all such advantages, will be of relatively simple and inexpensive construction.

The above mentioned desirable objects are attained by the novel features of construction, combinations and relations of parts hereinafter described, illustrated in the accompanying drawing and covered in the claims.

In the drawing, the invention is disclosed in one practical embodiment, but it will be understood that the actual physical structure may be modified and changed in various ways all within the true spirit and scope of the invention.

Fig. 1 is a broken plan view showing an embodiment of the binder in an intermediate or partly open position.

Fig. 2 is an enlarged broken and part sectional view showing the binder in closed position.

Fig. 3 is a part sectional and end view of the binder in closed condition.

Fig. 4 is a generally similar view showing the binder fully opened.

In the several views, the cooperating ring constituting elements are designated 1, and are shown as being attached to and carried by base plates or levers 8, having hinging engagement within the inturned edge flanges 9, of the resilient channel shaped back member 10.

The inner opposing edges of the ring carrying plates 8, are shown as notched at 11, to receive the notched portions 12, of the intermediate couplers or connecting links 13. These links are shown as having parallel sided guiding projections 14, operating through guide slots 15, in the cover plate 16, secured in arched relation over the concave face of the back plate.

Bridge plates 17, engaged by flanges 9 of the back plate at opposite sides of the ring hinge plates 8, carry bearings 18, for a rock shaft 19, having cam or crank portions 20, engaged in the transverse slots 21, in the connecting or equalizing links 13.

A crank handle 22, at one end of the rock shaft 19, provides convenient means for operating the same and this handle may overlie the end bridge piece 17, as in Fig. 2, so that the latter will serve as a stop to limit the turning movement of the rock shaft in either direction.

With the parts in the position shown in Figs. 2 and 3, that is, with the intermediate connecting link retracted and held so by the inwardly turned

crank 20, the ring elements are rocked together and held so by the approximate dead center position of the crank. The binder ring is thus locked against opening and can only be released by turning the hand crank in the right-handed direction 5 indicated by the arrow 23, in Fig. 3.

Similarly, when the handle 22 is rocked all the way to the right as in Fig. 4, the crank 20 will stand approximately in the upper dead center position, locking the ring forming elements in the 10 open relation shown.

The hinge plates 8 of the ring elements form in effect leverage extensions at the bases of these ring elements, enabling the intermediate connecting link to forcibly rock the ring elements open 15 and closed with relatively small effort applied to the hand crank 22. In coming to the closed relation illustrated in Fig. 3, the tips of the ring forming members may come together before the crank reaches the ends of its throw, in which 20 event, the supporting plate or plates 17, may be sprung upward slightly substantially as indicated in this view, to add a certain spring force tending to hold the rings closed and to compensate for such slight variation in size of parts as may occur 25 in production manufacture.

The various parts of the device are rugged and relatively simple, inexpensive to manufacture and assemble and there are no springs or fragile parts liable to break or get out of order. The structure 30 may be varied in many ways within the scope of the invention. The structure lends itself to individually locked binders by constructing the shaft 19, so that it may be turned only by one having the proper key. For example, in place of 35 the simple hand crank 22, the end of shaft 19 may be finished off with an angular head adapted to be turned only by a key of that particular cross-section. The terms employed herein therefore are to be considered as used in a descriptive 40 rather than in a limiting sense, except possibly as limitations may be required by state of the prior art.

What is claimed is:

1. A ring binder, comprising end-to-end opposed levers pivotally supported at their outer ends, a link loosely interposed between and pivotally connecting the inner ends of said levers, a rotative member having a crank portion operatively engaged with said link, cooperating binder 45 ring constituting elements carried by said levers and guide means slidingly confining said link to straight in and out movement between the opposed inner ends of said levers.

2. A ring binder, comprising cooperating binder 55 ring constituting elements, hingedly supported and having opposed leverage extensions, a link interposed between said leverage extensions, said link and leverage extensions having interlocking notched engagement with notched portions in 60

opposite edges of said link engaged in notched portions in opposed inner edges of said leverage extensions, means for guiding said link in a straight in and out movement and a rotary member having a crank portion engaged with said link.

3. A ring binder, comprising cooperating binder ring constituting elements, hingedly supported and having opposed leverage extensions, a link interposed between said leverage extensions, said link and leverage extensions having interlocking notched engagement, a rotary member having a crank portion engaged with said link and a guide for confining said link to rectilinear movement.

4. A ring binder, comprising pivotally supported cooperating binder ring constituting elements having opposed base portions notched in their opposing edges, an intermediate link having a notched opposite edges entered in the notches of the base portions of the ring constituting elements and a rotatively mounted member having a crank portion engaged with said link.

5. A ring binder comprising a channel shaped back having edge flanges, a supporting plate in said back and held by said edge flanges, opposed levers rockingly held at their outer ends by said edge flanges, a rock shaft pivotally mounted on said supporting plate and having a crank portion adjacent the inner ends of said oppositely disposed levers, a link connecting the inner ends of said levers and engaged on the cranked portion of said rock shaft and binder ring constituting elements carried by said levers.

6. A ring binder comprising cooperating back plate and cover plate, a supporting plate between said back plate and cover plate, a rock shaft journaled on said supporting plate, opposed levers between said back plate and cover plate and pivotally supported at their outer ends, binder ring constituting elements projecting from said levers, links connecting the inner ends of said levers, said cover plate having guide openings for said links and cranked portions on said rock shaft engaged with said links for operating the same in said guide openings.

7. A ring binder, comprising spaced opposed supporting flanges, end-to-end opposed levers interposed between said flanges and having their outer ends rockingly engaged with said flanges, a member interposed between and having notched opposite edges engaged over the inner ends of said levers for spacing said levers in rocking engagement with said supporting flanges and for coupling the inner ends of said levers together and thereby requiring the same to rock in unison, cooperating binder ring constituting elements projecting from said levers, supporting means bridging said flanges at the side of said rock levers and a rock shaft journaled on said supporting means and extending longitudinally of said binder substantially at a right angle to the plane of said binder ring constituting elements, said rock shaft having a cranked portion adjacent the inner ends of said oppositely disposed levers and extending through said coupling member for effecting in and out movement of the same necessary to rock the levers for relatively opening and closing the binder ring constituting elements.

8. A ring binder, comprising end-to-end opposed levers, a member coupling the inner ends

of said levers together and thereby requiring the same to rock in unison, cooperating binder ring constituting elements projecting from said levers and a rock shaft extending longitudinally of said binder substantially at a right angle to the plane of said binder ring constituting elements, said rock shaft having a cranked portion adjacent the inner ends of said oppositely disposed levers and extending through said coupling member for effecting in and out movement of the same necessary to rock the levers for relatively opening and closing the binder ring constituting elements, said rock shaft having an oscillating movement sufficient to carry the cranked portion to approximate dead center positions at the inner end outer limits of movement of the coupling member and resilient means for yieldingly retaining said rock shaft in said approximate dead center positions.

9. A ring binder, comprising end-to-end opposed levers, a member coupling the inner ends of said levers together and thereby requiring the same to rock in unison, cooperating binder ring constituting elements projecting from said levers and a rock shaft extending longitudinally of said binder substantially at a right angle to the plane of said binder ring constituting elements, said rock shaft having a cranked portion adjacent the inner ends of said oppositely disposed levers and extending through said coupling member for effecting in and out movement of the same necessary to rock the levers for relatively opening and closing the binder ring constituting elements and a cover plate over said levers and intermediate coupling member, said coupling member having a portion operating through said cover plate as a guide.

10. A ring binder, comprising a channel-shaped back having edge flanges, opposed levers rockingly held at their outer ends by said edge flanges, coupling members interposed between the inner opposed ends of said rocking levers and holding said levers spread apart in rocking engagement with said edge flanges, supporting elements bridging the channel-shaped back at opposite sides of the rocking levers and supported by said edge flanges and a crank shaft journaled on said supporting elements and having cranked portions extending through said coupling members for effecting movement of the latter to rock said opposed levers in binder ring opening and closing movements.

11. A ring binder, comprising a channel-shaped back having edge flanges, opposed levers rockingly held at their outer ends by said edge flanges, coupling members interposed between the inner opposed ends of said rocking levers and holding said levers spread apart in rocking engagement with said edge flanges, supporting elements bridging the channel-shaped back at opposite sides of the rocking levers and supported by said edge flanges and a crank shaft journaled on said supporting elements and having cranked portions extending through said coupling members for effecting movement of the latter to rock said opposed levers in binder ring opening and closing movements and a cover plate engaged over the edge flanges of said channel back and having guide openings slidably receiving portions of said coupling members.

CHARLES C. CRUZAN.
